UNITED STATES PATENT OFFICE

WILLIAM C. DEVEREAUX, OF DETROIT, MICHIGAN

MEANS FOR ASSEMBLING LATCHES FOR VEHICLE DOORS

Application filed November 12, 1927. Serial No. 232,843.

This invention relates to latches for vehicle doors and the like and particularly to means for facilitating the assembly upon a door-latch (or the dis-assembly therefrom) of an actuating element for the bolt of said latch.

5 My co-pending application, Serial No. 188,720, filed May 4, 1927, discloses a bolt-actuating handle-shaft having a polygonal end portion adapted to operatively fit a polygonal opening formed in a cam member or the like transmitting control from said handle-shaft to a latch bolt, and a metal plate formed with a similar polygonal opening is fixedly mounted in such relation to said cam member that the handle shaft must be fitted 10 through the opening member and can be withdrawn from the cam member only when the opening of the latter is definitely registered with that of said metal plate.

15 It is a primary object of the present invention to provide a method and means for temporarily holding a rotative cam member, or a like rotative bolt-actuating element, in a position to definitely register a polygonal opening in said member with a similar opening in an adjacent fixed metal plate so as to permit 20 an insertion (or withdrawal) through said plate and into (or from) said cam member of a handle shaft having an end portion of the same polygonal form as said openings.

25 These and various other objects the invention attains by the construction hereinafter described and illustrated in the accompanying drawings, wherein:

30 Figure 1 is a view in side elevation of one type of vehicle door latch to which the present invention is applicable.

35 Figure 2 is a similar view showing the bolt of said latch held retracted by the invention.

40 Figure 3 is a transverse vertical sectional view taken upon the line 3—3 of Figure 2.

45 Figure 4 is a horizontal cross sectional view taken upon the line 4—4 of Figure 1.

50 Figure 5 is an end view of said latch and

55 Figure 6 is a similar view showing an alternative provision for temporarily maintaining the latch bolt retracted.

60 In these views the reference characters 1 and 2 designate respectively the outer and inner panels of a vehicle door. Within said

door is arranged a latch, comprising mounting formed by parallel plates 3 and 4, the former being relatively large and disposed adjacent to the inner panel 2. The relatively small mounting plate 4 of said latch lies adjacent to the outer panel 1 and has secured thereto and spaced therefrom a plate 5 forming with said plate 4 a casing receiving a rotative hub member 6 for a cam member 7. Said cam member is connected to the hub 6 by 65 a U-shaped yoke element 8 which projects toward the free edge of the door and which has its outer portion journaled upon the plate 3 as indicated at 9. Said yoke is for the purpose of adapting the cam member 7 to 70 be mounted adjacent to the inner panel of the door and to be operated from the hub member 6 which is adjacent to the outer door panel. Said cam member, as is best seen in Figures 1 and 2, has the nature of an arm 75 downwardly projecting from the hub 6 and terminally bearing upon the forward edge of a sliding plate 10 which is shouldered, as indicated at 11, to retract a bolt 12 when said hub and cam member are rocked from the 80 position shown in Figure 1 toward that illustrated in Figure 2. The bolt 12 and its actuating plate 10 are mounted upon the larger mounting plate 3 of the lock and are guided in their sliding travel in any suitable 85 manner as for example by the plate 13 carried by and inwardly spaced from the plate 3. A suitable coiled spring 14 urges the bolt 12 normally to its projected position, as appears in Figure 1, and acts through the slide plate 10 upon rotary unit 6, 7, 8 tending to maintain the position thereof also shown in Figure 1.

90 The cam member 7 is formed at its axis with an opening 15 of a square or other polygonal shape and a handle shaft 16 has a similar polygonal end portion 17 adapted to operatively fit the opening 15.

95 Exterioly carried by the mounting plate 4 of the latch (or otherwise fixedly mounted adjacent to the outer panel 1) is a plate 18 in which is formed a square or other polygonal opening 19 corresponding in size to said opening 15, but having its walls in an angular 100 relation to those of the opening 15, when the

bolt 12 is in latching position and the unit 6, 7, 8 is in corresponding position, as best appears in Figure 1. When, however, said unit is in a definite position, intermediate its respective limiting positions, the openings 15 and 19 are accurately registered as appears in Figure 2.

It is a purpose of the present invention primarily to provide a means for temporarily maintaining the unit 6, 7, 8 in the position illustrated in Figure 2 by mechanical means so as to permit the handle member 16, 17 to be readily engaged with or dis-engaged from the hub 6. For this purpose the yoke member 8 is formed adjacent to the plate 4 with an upstanding lug 20 and a pair of openings 21 are formed in the plates 4 and 13 to receive a pin 22 which, when entered in said openings, is engageable by the lug 20 to maintain the intermediate position of the unit 6, 7, 8 shown in Figure 2. When the handle shaft 16 has been properly assembled with the latch, the pin 22 may be readily withdrawn. Preferably the openings 21 which are adapted to receive the pin 22 further function to receive a screw (not shown) for holding an escutcheon plate 23 upon the outer panel member 1.

In place of forming the lug 20 upon the yoke 8 for engagement by the pin 22 it is feasible to insert such a pin, as indicated at 24 in Figure 6, in an opening 25 formed in an end face of the door 1 whereby said pin is adapted to maintain the desired position of the unit 6, 7, 8 through engagement by the yoke element 8.

The described means for assembling a handle shaft 16, 17 upon a door latch permits such assembly to be accomplished with a minimum loss of time and said means may furthermore be used to advantage whenever it is desired for any reason to detach said handle member from the latch.

While it will be apparent that the illustrated embodiments of my invention herein disclosed are well calculated to adequately fulfil the objects and advantages primarily stated, it is to be understood that the invention is susceptible to variation, modification and change within the spirit and scope of the subjoined claims.

What I claim is:

1. The combination with a rotary member formed with a polygonal opening, of a bolt adapted for retraction by said rotary member, a handle shaft having a polygonal portion proportioned to fit in said polygonal opening to adapt said rotary member for actuation by said handle shaft, a plate fixedly mounted adjacent to said rotary member and formed with a polygonal opening substantially duplicating that of said rotary member means normally maintaining a position of said rotary member, acutely inclining the walls of the polygonal opening of said member to the walls of the polygonal open-

ing in said plate, said rotary member being formed with a projection substantially transverse to the axis of rotation of said member, and a mounting for the specified parts, having spaced walls provided with aligned openings positioned so that said projection has to be moved just beyond the aligned openings when the said polygonal openings are brought in register, whereby a stop pin may be inserted in the aligned openings for mechanically holding said rotary member in a position registering its opening with that of said plate.

2. The combination with a rotary member formed with a polygonal opening and a lug extending radially of such opening, of a bolt adapted for retraction by said rotary member, a handle shaft having a polygonal portion proportioned to fit in said polygonal opening to adapt said rotary member for actuation by said handle shaft, a plate fixedly mounted adjacent to said rotary member and formed with a polygonal opening substantially duplicating that of said rotary member, means normally maintaining a position of said rotary member whereby the walls of its polygonal opening are out of alignment with the walls of the polygonal opening in said plate, and a mounting for the said parts having a pair of spaced walls on opposite sides of said lug and provided with aligned openings arranged to be passed by said lug in its movements to and from its normal and retracted positions, whereby a stop pin may be inserted in said openings to be engaged by said lug to hold the rotary member in a position registering its opening with that of said plate.

In witness whereof I hereunto set my hand.

WILLIAM C. DEVEREAUX.
